CLAIM

The ornamental design for a wire shelving unit for canned goods, as shown and described.

DESCRIPTION

FIG. 1 is a perspective view of a wire shelving unit for canned goods showing my new design;

FIG. 2 is a front elevational view;

FIG. 3 is a top plan view;

FIG. 4 is a left side elevational view, the right side being a mirror thereof;

FIG. 5 is a perspective view of a second embodiment of the shelving unit shown in FIG. 1;

FIG. 6 is a front elevational view;

FIG. 7 is a top plan view;

FIG. 8 is a left side elevational view, the right side being a mirror image thereof;

FIG. 9 is a perspective view of a third embodiment of the shelving unit shown in FIG. 1;

FIG. 10 is a front elevational view;

FIG. 11 is a top plan view;

FIG. 12 is a left side elevational view, the right side being a mirror image thereof;

FIG. 13 is a perspective view of a fourth embodiment of the shelving unit shown in FIG. 1;

FIG. 14 is a front elevational view;

FIG. 15 is a top plan view; and

FIG. 16 is a left side elevational view thereof, the right side being a mirror image thereof.
